HIGH VOLTAGE DISCONNECTING SWITCH

Arnold E. Brock, Burlingame, and Ernest H. Gremminger, Mill Valley, Calif., assignors to Pacific Electric Manufacturing Corporation, San Francisco, Calif., a corporation of California

Application January 2, 1940, Serial No. 312,046

4 Claims. (Cl. 200—48)

The present invention relates to air break switch apparatus and more particularly to disconnecting switches of the outdoor type used in sectionalizing and interrupting high potential 5 electrical transmission lines.

An object of the invention is to provide an improved high voltage circuit interrupting switch and operating means therefor which may be adapted for use on single and multiphase electric power transmission lines, where it is desired to 10 sectionalize the transmission line or to connect or disconnect a branch circuit at points of intersection with the main power line, as at a substation.

Another object of the invention is to provide 15 an improved operating means for a disconnecting switch of the above character in which the position of the switch blade is at all times positively controlled by its operating mechanism.

Another object of the invention is to provide 20 a high contact pressure producing mechanism for disconnecting switches that is adapted to be operated by the switch blade operating mechanism when the switch blade has been moved into 25 co-operating relation with its stationary contact.

Another object of the invention is to provide 30 a new and novel form of switch blade controlling and contact pressure producing mechanism in which the switch blade operating mechanism will be rendered operative to actuate the contact pressure producing mechanism when the switch has been moved into its circuit closed position without imparting a further closing movement to the 35 switch blade.

Switches of the character contemplated by this invention are generally mounted in the open where, in cold climates, they are subjected to the accumulation of ice and snow which may interfere with their successful operation. Therefore, 40 it is another object of the invention to provide a switch blade of improved construction having relatively movable parts out of contact with a stationary cooperating clip which will serve to break and dislodge any accumulation of ice at 45 the end of the switch blade prior to any movement thereof from its circuit closed position.

A further object of the invention is to provide 50 a novel construction for disconnecting switches of the type having high contact pressure producing means in which additional means is associated with the high contact producing mechanism that will operate, prior to an opening operation of the switch blade, to break any ice which may have 55 accumulated upon the stationary contact at the

end of the switch blade when the switch blade is in its closed circuit position.

With the above and other objects in view, the present invention contemplates a special form of switch blade high contact pressure producing 5 means and an improved actuating mechanism therefor which will operate to establish a high contact pressure between the switch blade and the stationary contact after the switch blade has been moved into its final circuit closed position, 10 and which will also function to dislodge any accumulated ice and at the same time relieve the high contact pressure between the switch blade and the stationary contact before it becomes operative to move the switch blade into its open 15 circuit position.

For a better understanding of the invention reference should be had to the accompanying drawings, wherein there is shown by way of illustration and not of limitation, preferred em- 20 bodiments thereof.

In the drawings:

Figure 1 is a side elevation of a single pole disconnecting switch constructed in accordance with 25 this invention.

Figure 2 is a fragmentary plan view with parts broken away and in section showing the operating portions of the switch illustrated in Figure 1 of the drawings.

Figure 3 is a fragmentary side view, partially 30 in section, of the switch as illustrated in Figure 2.

Figure 4 is a side view, partially in section, and with parts broken away to illustrate the condition of the operating mechanism when the switch blade is in its circuit open position.

Figure 5 is a sectional view taken along line 35 V—V of Figure 3 looking in direction of arrows.

Figure 6 is a horizontal sectional view taken at the end of the switch blade and showing the high contact pressure producing mechanism.

Figure 7 is a vertical sectional view taken along line VII—VII of Figure 6 looking in direction of arrows.

Figure 8 is an end view with parts broken 45 away and in section to show further details of construction, and

Figure 9 is a fragmentary side elevation of the stationary contact engaging end of the switch blade.

In the operation of high voltage disconnecting switches of the type contemplated by the present invention, it is desirable that the switch be so constructed that the movable switch blade will engage the stationary contact with a high contact pressure and where the switch blade is 50 55

of considerable length, it is also desirable that the switch blade be movable into and out of its circuit closed position without requiring the exertion of an excessive operating force by its operating mechanism. In other words, while it is desirable to have a high contact pressure, it is also important that the means provided for attaining this result be of such a character as to not interfere with the free closing and/or opening movement of the switch blade with respect to its cooperating stationary contact.

For the purpose of illustration, the invention is shown in the drawings as embodied in a single pole switch. It is to be understood, however, that switches made in accordance with this invention may be provided for multiphase circuits by merely mounting any number of these switches side by side upon a suitable support and providing a common operating means therefor.

Reference is now made to Figure 1 of the drawings, wherein the switch contemplated by the present invention is shown as having a blade 10 that is pivotally mounted upon a supporting member 11 carried by a stand of insulators 12. At the outer free end of the switch blade 10 there is a stationary contact 13 that is mounted upon a similar stand of insulators 14. Arranged opposite the stand of insulators 14 and in spaced relation with the stand of insulators 12, there is a third stand of insulators 15 which, unlike the stand of insulators 12 and 14, is adapted to be rotated about its vertical axis. At the upper end of the stand of insulators 15 there is an operating crank arm 16 that is adapted, through a connecting rod 17, to move the switch blade 10 between its closed and open circuit positions, and to also operate a high contact pressure producing mechanism carried by the switch blade 10, as will hereinafter appear. The upper end of the stand of insulators 15 is shown as journaled in spaced relation with the stand of insulators 12 by means of a current conducting strut 18 and at its lower end the stand of insulators 15 has an operating lever 19, or other suitable means, by which it may be rotated through an arc sufficient to effectively move the switch blade 10 between its open and closed circuit positions, as is well understood in the art.

For the purpose of establishing a connection between the switch and the conductors of a power circuit, the stationary contact 13 carries an outwardly extending terminal 20 to which a line conductor 21 is adapted to be connected and the current conducting strut 18 has a similar outwardly extending terminal 22 to which a line conductor 23 is adapted to be connected. In order to complete the circuit between the terminals 20 and 22 in an effective manner and provide a good current conducting path between the movable switch blade 10 and the stationary current conducting strut 18, there is a pair of flexible jumpers or shunts 24 through which the current may pass from the current conducting strut 18 to the movable switch blade element. With the switch here illustrated it will be understood that arcing horns of any suitable type may be provided, if desired.

Reference is now made to Figures 2, 3, 4 and 5 of the drawings for a detailed description of the switch blade operating mechanism. As shown in these figures of the drawings, the supporting member 11 has two spaced up-standing pedestal forming portions between which there is fixed a non-rotatable shaft 25 that provides a pivotal axis about which the switch blade 10 is movable.

The switch blade 10 is carried by an enclosing housing 26 which is journaled at its sides upon the non-rotatable shaft 25. In addition to the switch blade 10, the enclosing housing 26 also carries an outwardly disposed shaft 27 to which there is fixed a pair of spaced lever arms 28 that connect with the end of the operating rod 17, through a swivel connection 29. These lever arms 28 are positioned one at each end of the shaft 27 and mounted centrally upon the shaft 27 and 10 extending downwardly within the housing 26 there is a third lever arm 30 which is likewise fixed upon the shaft 27 so that the lever arms 28 and 30 will act as a single double ended lever. Located within the enclosing housing 26 and 15 connected with the end of the lever arm 30 there is an axially movable bifurcated member 31 having forked side portions 32 at one end which slidably engage the non-rotatable shaft 25. At its other end the axially movable bifurcated member 31 is connected to an operating rod 33 which extends outwardly through the tubular switch blade 10 and connects with a high contact pressure producing mechanism to be hereinafter described. Mounted between its forked side portions 32 the movable bifurcated member 31 carries a cam engaging roller 34 which is adapted to cooperate, as will hereinafter appear, with a stationary concentric cam 35 located centrally upon the non-rotatable shaft 25. Cooperating with 30 the bifurcated member 31 the enclosing housing 26 also carries an adjustable stop 36 that serves to limit the outward movement of the bifurcated member 31. In order to facilitate an assembly of these parts, the enclosing housing 26 is shown 35 as having a removable cover plate 37. The enclosing housing 26 is also shown as provided with an outwardly extending arm 38 that carries an adjustable stop forming means 39 which engages with an abutment 40 upon the supporting member 11 when the switch blade is in its circuit 40 closed position.

Before proceeding further with a detailed description of the high contact pressure producing means provided by the present invention, attention is directed to Figure 2 of the drawings, where it will be noted that the operating crank arm 16 and the third stand of insulators 15 are connected together by a shaft 41 which is supported upon bearings 42 carried by the current conducting strut 18. As here shown, the shaft 41 is keyed at its upper end to the operating crank 16 and at its lower end it is keyed to a flanged insulator engaging cap 43.

Reference is now made to Figures 6, 7, 8 and 9 55 of the drawings for a detailed description of the high contact pressure producing means referred to hereinabove as located at the stationary contact engaging end of the tubular switch blade 10. As shown in these figures of the drawings, the 60 outer contact engaging end of the tubular switch blade 10 carries a contact making member 44 that has vertical stationary contact engaging sides which, together with cover forming plates 45 and 46, form a box-like structure at the end of 65 the switch blade 10 in which the contact pressure producing means is located. These cover forming plates 45 and 46 are adapted to move axially with respect to the stationary contact 13 when the contact pressure producing mechanism 70 at this end of the switch blade 10 is operated by movement of the operating rod 33. As shown in Figure 7, the cover forming plates 45 and 46 are held upon the contact member 44 by means of a tie-bolt 47 and at their outer ends they slidably 75

engage guide plates 48 and 49 respectively. The guide plates 48 and 49 are shown as secured at one side only to one of the spaced vertical contact engaging sides of the contact member 44 so as not to interfere with a relative movement between these parts. These guide plates 48 and 49 also cooperate with the movable cover forming plates 45 and 46 to maintain the enclosure of the contact pressure producing mechanism which is to be presently described. At this point it will also be noted that the contact making member 44 carries an end closure plate 50 that serves to complete the enclosure of the contact pressure producing mechanism. This end plate 50, like the guide plates 48 and 49, as illustrated in Figure 8, is secured by means of screws 51 to only one of the vertical sides of the contact member 44 so that the vertical contact engaging sides of the contact member 44 may move toward and away from each other. At the inner end of the contact member 44 the vertical sides thereof terminate as a tubular extension 52 that is secured in the end of the tubular switch blade 10. Slidably mounted within this tubular extension 52 of the contact member 44 there is a movable piston-like guide 53 to one side of which the end of the operating rod 33 is connected. At the other side of the piston-like guide 53 there is an outwardly extending portion 54 that has spaced ears 55 through which the tie-bolt 47 extends. With this arrangement it will be understood that when the operating rod 33 is moved axially within the tubular switch blade 10, the piston-like member 53 with the extension 54 will be likewise moved and thus carry the tie-bolt 47 and the cover forming plates 45 and 46 axially of the contact member 44. In addition to engaging the tie-bolt 47, the outwardly extending portion 54 of the guide member 53 also supports oppositely arranged spring bars 56 and 57. These spring bars 56 and 57 are loosely secured upon the extending portion 54 by means of a bolt 58 and extend forwardly between the spaced ears 55 of the extending portion 54 with one on each side of the tie-bolt 47. Outwardly with respect to the tie-bolt 47, the spring bars 56 and 57 are engaged by anti-friction rollers 59 and 60 carried by the vertical contact engaging side portions of the contact member 44. As shown in the drawings, these anti-friction rollers 59 and 60 are positioned upon a vertical axis substantially in alignment with the blade engaging surfaces of the stationary contact 13. Outwardly with respect to their point of engagement with the anti-friction rollers 59 and 60, the spring bars 56 and 57 are provided with raised wedge or cam forming members 61 and 62 which are adapted to be drawn under the anti-friction rollers 59 and 60 when the operating rod 33 is moved to the right by the switch blade operating mechanism previously described. With this arrangement it will be readily seen that when these wedge or cam forming members 61 and 62 are drawn into alignment with the anti-friction rollers 59 and 60, the spring bars 56 and 57 will be flexed intermediate their ends over the tie-bolt 47 and exert a spring action that will tend to move the vertical sides of the contact member 44 away from each other and thus establish a high contact pressure at their points of engagement with the stationary contact 13. At the same time the cover forming plates 45 and 46, which are out of engagement with the stationary contact 13, will be moved axially with respect to the switch blade 10. At this point it should be pointed out that the purpose in providing the contact member 44 with these mov-

able cover forming plates 45 and 46 is to dislodge any snow and/or break away any ice which may accumulate upon the switch at this point. Therefore, the cover forming plates 45 and 46 each have a stepped or inclined ridge 63 positioned at the outer ends thereof which extends transversely thereto. With this arrangement, when the cover forming plates 45 and 46 are moved, as upon an operation of the contact pressure producing means, as indicated above, the transversely extending ridges 63 will be drawn into a position substantially in alignment with the opposed sides of the stationary contact 13. During the reverse operation of the contact pressure producing mechanism, that is an operation thereof which will remove the contact pressure between the contact member 44 and the stationary contact 13 preparatory to an opening of the switch, these ridges 63 will move outwardly with respect to the stationary contact 13 and due to their particular configuration they will function to fracture and dislodge any snow or ice which might be present upon the stationary contact 13 at the end of the switch blade 10. As an additional feature, it will be noted that the stationary contact 13 and the vertical stationary contact engaging sides of the contact member 44 are each provided with cooperating surfaces of silver 64 which, as is well understood in the art, avoids and/or reduces to a minimum the danger of corrosion of these surfaces and insures a good current conducting contact.

It is believed that the operation of the switch here disclosed will be clearly evident to those skilled in the art. However, in order that there be no misunderstanding in this connection, it may be stated that when the switch is in its circuit closed position, as illustrated in Figure 1 of the drawings, the internal switch blade operating mechanism will be in the positions illustrated in Figure 3 of the drawings, with the cam engaging roller 34 positioned below and in abutting relation with the end of the stationary concentric cam 35. Now, with the operating mechanism in this condition, it will be understood that when the operating crank arm 16 is rotated in a counter-clockwise direction, as viewed in Figure 2 of the drawings, the connecting rod 17 will be moved to the right and thus cause the levers 28 and 30 to rotate in a clockwise direction about the shaft 27 carried by the enclosing housing 26. This movement of the levers 28 and 30 will cause the bifurcated member 31 to move toward the left and carry the cam engaging roller 34 out of abutting relation with the end of the stationary concentric cam 35. At the same time the lever arm 30 will be moved into engagement with the adjustable stop 36 after which further movement of the connecting rod 17 will cause the enclosing housing 26 to rotate about the stationary shaft 25 and thus carry the tubular switch blade 10 upwardly and out of circuit making engagement with the stationary contact 13. During this operation of the switch blade 10, the cam engaging roller 34 will only lightly engage the concentric surface of the stationary cam 35, as practically all of the switch blade opening force exerted in this manner will be exerted upon the stationary adjustable stop 36 carried by the enclosing housing 26. Now, with the switch blade 10 in its full open position, as illustrated in Figure 4 of the drawings, it will be readily seen that upon a reverse rotation of the operating crank arm 16 the connecting rod 17 will be caused to move to the left and exert a switch

blade closing force upon the levers 28 which are connected to the enclosing housing 26 by the shaft 27. During this closing movement of the switch blade 10, the cam engaging roller 34 will 5 engage the stationary cam 35 with a rolling contact and thus prevent any movement of the operating rod 33 which, as has been pointed out, connects with the high contact pressure producing mechanism at the contact engaging end of 10 the switch blade 10. By the time the switch blade 10 has been moved into its horizontal position and in engagement with the stationary contact 13 the cam engaging roller 34 will have moved down into a position clear of the concentric stationary 15 cam 36. Further movement of the connecting rod 17 will then cause the levers 28 and 30 to rotate with the shaft 27 and move the bifurcated member 31 to the left and thus exert a pulling force upon the operating rod 33. This movement 20 of the operating rod 33 will move the piston-like guide 53 to the right, as viewed in Figures 6 and 7 of the drawings, and as a result the wedge or cam forming members 61 and 62 carried respectively by the spring bars 56 and 25 57 will be drawn into pressure exerting relation with the anti-friction rollers 59 and 60 and thus as a final operation of the switch operating mechanism, establish a high contact pressure between the opposed contact making surface of 30 the stationary contact 13 and the contact member 44 at the end of the switch blade 10. At this point it will be also understood that upon a reverse movement of the operating rod 33 the wedge or cam forming members 61 and 62 will be 35 moved out of engagement with the anti-friction rollers 59 and 60 and thus permit the sides of the contact member 44 to assume their normal position where substantially no contact pressure will exist between the stationary contact 13 and 40 the contact member 44. After this has occurred, the switch blade 10 may be moved out of engagement with the stationary contact 13 without requiring any more operating effort than that necessary to move the switch blade 10 into its 45 circuit open position. At the same time it will be understood that the cover forming plates 45 and 46 will be likewise moved to the left, as viewed in these figures of the drawings. Now, should 50 there be any accumulation of ice upon the stationary contact 13, it will be seen that the ridges 63 provided upon the cover forming plates 45 and 46 will move outwardly and exert a fracturing force that will dislodge any accumulation of ice and permit a free opening of the switch under 55 these extreme conditions.

While we have, for the sake of clearness and in order to disclose the invention so that the same can be readily understood, described and illustrated specific devices and arrangements, we 60 desire to have it understood that this invention is not necessarily limited to the specific means disclosed, but may be embodied in other ways that will suggest themselves to persons skilled in the art. It is believed that this invention is new 65 and it is desired to claim it so that all such changes as come within the scope of the appended claims are to be considered as part of this invention.

Having thus described our invention, what we 70 claim and desire to secure by Letters Patent is—

1. In a disconnecting switch of the character described, the combination of a stationary contact having opposed contact making surfaces, a switch blade having side portions adapted to be 75 fixed into high contact engagement with the op-

posed surfaces of said stationary contact, means for flexing the side portions of said switch blade into high contact making engagement with the contact surfaces of said stationary contact, an operating rod extending longitudinally of the 5 switch blade for actuating said means for flexing the side portions of the switch blade, a cover forming member extending longitudinally of the switch blade and out of engagement with said stationary contact, and means connecting said 10 operating rod with said cover forming member adapted to move said cover forming member longitudinally of the switch blade as said first means is operated.

2. In a disconnecting switch of the character 15 described, the combination of a stationary contact having opposed contact making surfaces, a switch blade having side portions adapted to be flexed into high contact engagement with the opposed surfaces of said stationary contact, means 20 for flexing the side portions of said switch blade into high contact making engagement with the contact surfaces of said stationary contact, an operating rod extending longitudinally of the switch blade for actuating said means for flexing 25 the side portions of the switch blade, slideable means mounted at the top and bottom of the switch blade and out of engagement with said stationary contact, and a tie-bolt connecting said operating rod with said slideable means adapted 30 to move said slideable means longitudinally of the switch blade as said switch blade flexing means is actuated by said operating rod.

3. In a disconnecting switch of the character 35 described, the combination of a stationary contact having oppositely disposed contact making surfaces, a pivotally mounted switch blade having vertically disposed sides adapted to be moved into high pressure contact with the opposed surfaces of said stationary contact when the switch 40 blade is in its circuit closed position, opposed anti-friction roller means carried by the side portions of said contact member and located in line with the contact forming surfaces of the stationary contact, a longitudinally movable operating rod 45 carried by said switch blade, a tie-bolt carried by said operating rod and extending vertically between the spaced sides of said contact member, a pair of spring bars secured at one end to said operating rod and disposed one on each side of 50 said tie-bolt, wedge forming means at the ends of said spring bars adapted to engage the anti-friction roller means carried by the spaced sides of said contact member adapted when moved into engagement with said anti-friction roller means 55 to exert an expanding force that will establish a high contact pressure between the sides of said contact member and the contact forming surfaces of said stationary contact, and means carried by said tie-bolt cooperating with the spaced sides of 60 said contact member to form an enclosure for said spring bars and anti-friction roller means, said means being movable longitudinally upon the switch blade out of engagement with said stationary contact, whereby movement of said 65 means prior to a circuit opening movement of the switch blade will operate to fracture and dislodge any ice which may have accumulated at the stationary contact end of the switch blade.

4. In a disconnecting switch of the character 70 described, the combination of a switch blade, a stationary contact having opposed contact surfaces, a contact forming member at the end of said switch blade having spaced vertical sides adapted to engage the opposed contact surfaces 75

of said stationary contact, high contact pressure producing means located between the spaced sides of said contact member adapted to exert an expanding force and establish a high contact pressure between the spaced vertical sides of said contact forming member and said stationary contact, movable means for operating said high contact pressure producing means, cover forming members slidably mounted upon the top and bottom 5 of said contact forming member out of engage-

ment with said stationary contact, and means connecting said cover forming members with said movable means, whereby said cover forming members will operate to fracture and dislodge ice or other foreign matter as the high contact pressure producing means is operated to relieve the high contact pressure prior to an opening movement of the switch blade. 10

ARNOLD E. BROCK.
